TRAINING COMPUTER

Thomas C. Bartee, 34 Cary Ave., Lexington, Mass.

Filed Nov. 6, 1964, Ser. No. 82,510

Term of patent 7 years

(Cl. D26—5)

The single figure of which is a front perspective view of a training computer showing my new design, legible matter being shown in zigzag lines for illustrative purposes. The side not shown is substantially a mirror image of the side shown, while the rear is substantially plain and unornamented.

I claim:

The ornamental design for a training computer, substantially as shown and described.
